BUILDING UNIT

Filed June 12, 1961

Fig. 1

The image contains two technical drawings. The left drawing shows a curved panel assembly. A curved panel (31) is held in a frame (22) by a support (20). The panel is covered with a mesh (26) and has a hatched pattern (27). The frame is supported by a base (24) and has vertical supports (25, 28, 30) and a central support (29). The right drawing is a cross-sectional view of a rectangular frame (1) with a hatched pattern (13). The frame is supported by a base (6) and has a central support (11) and a side support (12).

BUILDING UNIT

Yvon Laurendeau, R.R. 3, Louiseville, Quebec, Canada
Filed June 12, 1961, Ser. No. 116,335

Claims priority, application Canada June 18, 1960
1 Claim. (Cl. 20—5)

The present invention relates to a building unit and more particularly to a pre-fabricated unit for use in the construction of floors, roofs, and walls.

The building unit in accordance with the present invention is an improvement over the unit illustrated and described in the Canadian Patent 542,053 dated June 11, 1957, by William H. Willatts and Alfred H. Cornwall.

The building units in accordance with this patent and in accordance with the present invention serve as means for molding concrete in the construction of floors, roofs, or walls, or directly as wooden reinforcement for floors, roofs or walls. The building unit in accordance with Canadian Patent 542,053 is essentially constituted by a series of trough-like elements arranged side by side and consisting of planks or boards disposed in two separate parallel planes, arranged in spaced and staggered relationship and united two by two by diverging boards, the unit being reinforced by end members disposed transversely to the unit. It should be noted that, in the building unit in accordance with this patent nailing of the diverging boards to the horizontal boards is required along the lower as well as the upper edges of said diverging boards and it is also necessary to use specially shaped lower boards or battens. This increases the cost of fabricating the unit in accordance with this patent.

The general object of the present invention resides in the provision of a building unit of the character described which is of simplified and relatively low cost construction because the time required for its construction is considerably decreased and the number of separate elements used is also decreased.

Another object of the invention resides in the provision of a building unit of the character described which has a better appearance for those uses of the unit wherein the latter remains visible or which confers a better appearance to the visible parts of floors, roofs or walls molded with the unit of the invention.

Another important object of the invention resides in the provision of a unit of the character described which is more rigid and has greater resistance to stresses and loading.

The foregoing and other objects of the present invention will become more apparent during the following disclosure and by referring to the annexed drawings, in which:

FIGURE 1 is a perspective view of a portion of a building unit in accordance with the invention;

FIGURE 2 is a cross section;

FIGURE 3 is a partial longitudinal section of one end of the unit; and

FIGURE 4 is a cross section of the apparatus used for forming the trough of laminated wood.

In the drawings, the same reference characters indicate the same elements.

The unit in accordance with the invention comprises a series of trough-like elements 1 made of laminated wood and longitudinally disposed side by side in equally spaced and parallel relationship. Each trough-like element 1 has a generally V-shaped cross-section with a curved bottom 2 and flat diverging sides 3. Each trough-like element 1 consists of a plurality of wood laminations glued or cemented together and bent in accordance with the conventional technique for the fabrication of laminated wood in sheet form. The upper longitudinal edges

2

4 of each trough 1 is cut at right angles with respect to the flat sides 3 and engages a groove or rabbet 5 made in the longitudinal edges of boards 6 which extends over the entire length of the trough-like elements 1 and are disposed in a common plane. There is one board 6 between each pair of contiguous troughs 1. The edges 4 of the trough-like elements 1 are nailed to boards 6 by nail 7. The edges 4 may also be glued within the grooves 5. Each unit may have one or several troughs 1. In the drawings, three such troughs are shown united two by two by the boards 6.

Boards 8 at the exterior of the unit have a width of about half the width of the boards 6 and are provided with a longitudinal groove 9 for receiving a tongue or lath 10 which serves as a junction with the exterior board 8 of a contiguous building unit.

Each unit is moreover provided with reinforcing transversely disposed members longitudinally spaced of the unit. There is an end reinforcing member at each end 20 of the unit which is constituted by an end reinforcing board 11 disposed in a plane perpendicular to the boards 6 and 8 and provided at its inner face with a groove 12 having a shape corresponding to the cross-sectional shape of the trough 1 in order to receive the end edge of said trough. The boards 6 and 8 protrude slightly from the end of the trough 1 and are nailed by nails 13 on top of the end board 11 as indicated in FIGURE 3. The board 11 is wider than the height of the trough in order to protrude downwardly from the curved bottom 2 of the trough 1, this bottom 2 being nailed to the board 11 by nails 14.

The reinforcing members may also include intermediate boards 15 also perpendicular to the boards 6 and 8. The boards 15 are cut out to form notches, the edges 16 35 of which are in contact with the exterior surface of the trough 1 and the cut out pieces 17, of slightly decreased dimensions, are inserted within the trough 1 in order to make contact with the inside of the trough in the plane of boards 15. Boards 15 and pieces 17 are secured to the trough 1 by nails 18 and the upper marginal portion of boards 15 is secured to the boards 6 and 8 by nails 19.

FIGURE 4 shows a section of an apparatus for fabricating the trough 1. A box 20 comprising a bottom 21 and side walls 22 is provided inside thereof with a metal mold 23, the cross-sectional shape of which corresponds to the exterior shape of trough 1. Mold 23 is secured to and is supported by a metal channel 24 having reinforcing webs 25. The apparatus is completed by a compression block 26 having an exterior surface 27 of a cross-sectional shape corresponding to the interior shape of trough 1. Block 26 has a sliding fit with the walls 22 and is pressed by cover 28, overlying block 26 and secured by bolts 29, anchored in walls 22 of box 20, and nuts 30.

In order to make a series of troughs 1, the required number of wood laminations for one trough, previously coated with an adhesive, are placed directly within the mold 23 and a spacing block 31 is then disposed within the top lamination, then another set of wood laminations 60 is disposed over the lowermost block 31 and thus several sets of laminations and spacer blocks 31 may be disposed in the box. Each spacer block 31 has lower and upper surfaces conforming to the interior and exterior of the curved bottom of the trough for the building unit. The assembly is then compressed by the compression block 26 by means of cover 28, bolts 29 and nuts 30. The resultant assembly may then be placed in an oven for accelerating the curing of the adhesive in conventional manner.

While a preferred embodiment in accordance with the present invention has been illustrated and described, it is understood that various modifications may be effected

without departing from the spirit and scope of the annexed claim.

What I claim is:

A building unit comprising pre-molded troughs disposed side by side and each made of laminated wood having a generally V-shaped cross-section with a curved bottom and flat diverging sides, spaced parallel boards disposed in a common plane and extending the entire length of the troughs and secured to the respective edges of said troughs at the longitudinal sides thereof, the longitudinal sides of said boards being rabbeted for receiving the edges of said troughs, and reinforcing members transversely disposed with respect to said trough and secured thereto and to said boards, said reinforcing members being longitudinally spaced along said troughs and including reinforcing members at each end of said unit, each consisting of a terminal board perpendicular to said first named boards and provided at its inner face with grooves each having a shape corresponding to the cross sectional shape of said troughs, the end edges of said troughs being inserted within said grooves, said first named boards protruding from the ends of said troughs

and overlying said terminal reinforcing boards, said reinforcing members further including reinforcing members disposed intermediate the ends of said unit and constituted by intermediate boards parallel to said terminal reinforcing boards and cut out to form notches, the edges of which are in contact with the exterior face of said troughs, and the cut out parts of which are inserted within and are in contact with the internal face of said troughs in a plane common to said intermediate boards, these intermediate boards being secured to the underside of said first named boards and to the bottom of said troughs.
